UNITED STATES PATENT OFFICE.

FREDERICK E. OWEN, OF EAST PALESTINE, OHIO.

DESIGN FOR A REFRACtORY HEATER PLATE.

Application filed May 21, 1926. Serial No. 17,806. Term of patent 14 years.

To all whom it may concern:

Be it known that I, FREDERICK E. OWEN, a citizen of the United States of America, residing at East Palestine, in the county of Columbiana and State of Ohio, have invented a certain new, original, and ornamental Design for Refractory Heater Plates, of which the following is a specification, reference being had to the accompanying drawing, forming a part hereof.

The single figure of the drawing is a top plan view of a refractory heater plate embodying my new design.

I claim:

The ornamental design for a refractory heater plate substantially as shown.

In testimony whereof, I have hereunto subscribed my name this 15 day of May, 1926.

FREDERICK E. OWEN.
